ELECTROMAGNETIC CONTACT DEVICE
John C. Davis, 44 Starr Lane, Jamaica Plain, Mass.
Filed Mar. 31, 1959, Ser. No. 803,269
4 Claims. (Cl. 299—87)

This invention relates to an electrical switch and more particularly comprises a new and improved positive acting contact device.

Snap acting switching devices now available have certain features which disqualify their use in many applications. For example, the force required to overcome a spring or raise a weight which provides the snap action of the switch is not always available. In some cases, this difficulty may be overcome by relaxing the spring or reducing the weight but unfortunately, this is often accompanied by arcing and high resistance at the contact points. In such devices as timers and counters, it is absolutely essential that the contact points open and close cleanly and that false repetition be avoided.

Generally problems arise either when the switch actuator moves slowly or when the actuator may stop at any unforeseen location. In this case, the contacts often are or remain closed beyond the intended period.

The primary object of my invention is to provide an actuating action for contacts which under positive action causes the contacts to open immediately after being closed by the actuator, even though the actuating motion may have been imperceptibly slow or hesitant.

Another important object of my invention is to prevent a single action of a switch actuator from closing the switch contacts more than once.

Another object of my invention is to provide a contact device which may be firmly closed with the slightest application of force.

Another object of my invention is to provide a contact device which automatically closes tightly immediately upon the initial touching of the contacts.

Still another important object of my invention is to provide a contact device which automatically closes and opens once only in response to a single actuation.

Yet another object of my invention is to provide a contact device which cannot arc or repeatedly close in response to a single actuation.

To accomplish these and other objects, several embodiments of my invention include among their important features a pair of contact points at least one of which is carried on a movable blade. An actuator operated by some external member is positioned to move the blade to close the contacts. The initial light closure of the contacts under the feeble torque of the actuator energizes a coil the flux of which is devoted solely to pressing the contacts more tightly together. Thus, the contact resistance decreases and the current flow increases in the circuit as a continuous and irreversible process. This insures a firm and positive closure of the contacts and avoids chattering and hesitating. In the same circuit another coil is energized and its flux acts to cause relative movement between the contacts as a sub-assembly, and the actuator. The relative movement may be described as a "step-over" movement in that it frees the actuator from its engagement with the contact blades so that their spring tension may open them which deenergizes the circuit and restores it to a normal condition. Due to the "step-over" feature of the mechanism, no further contact action can take place until further activity by the actuator. Another signal in the form of repeated or continued mechanical motion must arise from the actuator to effect any further contact operation. In other embodiments of my invention, the first coil is eliminated. Thus, the closing of the contacts by the actuator imme-

2

dately causes energization and operation of the coil to effect a relative movement between the contacts and the actuator and the release of the contacts.

These and other objects and features of my invention will be better understood and appreciated from the following detailed description of several embodiments thereof, read in connection with the accompanying drawings, wherein:

FIGURES 1, 2, 3, 4 and 5 are elevation views of five different embodiments of my invention;

FIGURE 6 is a side elevation view of the embodiment shown in FIGURE 5;

FIGURE 7 is an elevation view of still another embodiment of my invention; and

FIGURES 8 and 9 are diagrammatic views of a portion of the apparatus shown in FIGURE 7 and suggest the alternative positions of the assembly.

The embodiment of my invention illustrated in FIGURE 1 includes a pair of contacts 10 and 12 carried on blades 14 and 16 respectively. The contacts 10 and 12 are normally open as shown in the drawing and are controlled by an actuator 18 pivotally mounted at 20 on an armature 22 gravity biased against its stop. Obviously, wherever the requirements of a particular application preclude the use of gravity as a reliable bias in any of the embodiments of my invention the designs can equally embody a spring bias. When the actuator is turned clockwise as shown in FIGURE 1 it engages the lower portion of the blade 14 and moves the contact 10 into engagement with the contact 12.

A sprocket 24 illustrated diagrammatically and rotatable in the direction of the arrow 26 is disposed adjacent to the lower end of the lever 18 and when rotated as suggested pivots the actuator about the pivotal mounting 20 causing it to close the contacts 10 and 12 in the manner described. A coil 28 is disposed adjacent the end 30 of the armature 22 and when energized, pivots the armature about its pivotal support 32 in a clockwise direction from the normal position illustrated. The same action carries the actuator 18 upwardly above the end of the blade of the sprocket. The coil 28 is energized through an electrical circuit which includes the leads 34 and 36. The contacts 10 and 12 interrupt the lead 34, and, therefore, the coil may be energized only by the closing of the contacts.

In operation, as each blade of the sprocket 24 engages the lower end of the actuator 18, the actuator closes the contacts 10 and 12. Closed contacts 10 and 12 complete the circuit to the coil 28 causing it to become energized. The energized coil 28 attracts the armature 22 which carries the lower end of the actuator over the particular sprocket blade which effected the actuation. Thus, the actuator steps-over the end of the sprocket blade, is released, and free to pivot on its support 20 between the limits of the stops 38 and 40. The snap action of the blade 14 breaks the contacts cleanly and no arcing may occur.

It should be appreciated that each blade of the sprocket 24 can actuate the contacts just once because of the "step-over" action of the actuator. Moreover, regardless of the position in which the sprocket stops, the contacts can not remain closed, for once closed, the actuator assembly promptly causes them to open.

The embodiment of FIGURE 2 is very similar to that shown in FIGURE 1 and its operation will become apparent from the following brief description. A pair of blades 40 and 42 each carries one of the contacts 44 and 46 and the blades bias the contacts to an open position. A sprocket 48 having a plurality of actuating blades 50 turns in the direction of the arrow 52 and each blade 50 is adapted to move the blade 42 to the left as illustrated

to effect the closure of the contacts 44 and 46. The sprocket 48 is mounted for rotation on an armature 54 pivotally supported at 56. The sprocket is presumed to be driven either directly or indirectly through a shaft by a gear (not shown) mounted concentrically with the pivotal support 36. As a result, the motion of the armature 54 as it pivots on its support will not destroy the mesh of the sprocket and drive gear.

The armature 54 is biased to the position illustrated by a spring 58 and a coil 60 when energized moves the armature against the bias of the spring in a counter clockwise direction causing the end 62 of the armature to engage the pole piece 64. The coil is energized through a circuit which includes the contacts 44 and 46. In operation, as the sprocket 48 turns, its actuating blades 50 engage the stem 66 of the blade 42 moving it to the left and causing the contacts to close. The closed contacts 44 and 46 complete the circuit to the coil 60. The energized coil 60 attracts the armature 54 and causes the sprocket to move downwardly with it so that the blade 42 and particularly the stem 66 is freed of the actuating blade 50 and steps-over it. The "step-over" action is aided by the slight rotation of the sprocket 48 as it moves in an arc with the armature. Obviously, the embodiment of FIGURE 2 has all of the advantages of the previously described embodiment and therefore they need not be repeated.

In each of the embodiments of FIGURES 1 and 2 the closing of the contacts immediately sets into action the assembly which cause them to open. In the embodiments of FIGURES 3-6, an intermediate step is introduced into the action of the switch which presses the contacts more tightly together. This phenomenon will be described below in connection with those figures.

The embodiment of my invention shown in FIGURE 3, like that in FIGURE 1, includes a pair of contacts 68 and 70 secured to blades 72 and 74, respectively. The normally open contacts are controlled by an actuator 76 pivotally mounted at 78 on an armature 80 gravity biased against its stop. When the actuator pivots clockwise as shown, it engages the lower end of the blade 72 and moves it to the right to close the contacts.

A sprocket 82 rotatable in the direction of the arrow 84 has a number of blades 86, each of which is adapted to engage the lower end of the actuator 76 and cause it to pivot clockwise in the manner described above and close the contacts 68 and 70.

A pair of coils 88 and 90 are wound on a common core and each is electrically energized through a circuit which includes the contacts 68 and 70. The coil 88 controls a pivotally mounted armature 92 supported on a pin 94 and when energized draws the arm 96 of the armature to its pole piece 98. When the armature 92 is pivoted in this manner under the influence of the coil 88, its other arm 100 engages the angle or flange 102 of the actuator 76 causing a firmer engagement between the contacts 68 and 70. Thus, the armature 92 serves as a booster to form a tighter engagement between the contacts and prevents chattering, hesitating and arcing. Moreover, by firmly closing the contacts 68 and 70 the resistance at the point of contact is reduced, which allows a greater current to flow through the circuit. Thus, the coil 88 and its associated components are devoted solely to pressing the contacts together in response to the light closure of the contacts under the feeble torque of the actuator.

The second coil 90 controls the armature 80 which is pivotally supported on a pin 104. The armature 80 normally is positioned as shown in the drawing but is drawn upwardly about its pivot 104 in response to energization of the coil 90. When the armature 80 is moved upwardly in this manner, the flanged end 106 of the actuator 76 rides upwardly above the flange 108 on the end of the arm 100 of armature 92. If the sprocket 82 no longer engages the lower end of the actuator 76, the actuator will be free to rotate counter clockwise on the pivot point 78

and release the blade 72 carrying the contact 68. When released, the blade 72 moves to the left until it is engaged by the stop 109.

It will be noted that the circuit 110 is connected to a power source through the contacts 68 and 70 and that the circuit includes two parallel branches for energizing the separate coils 88 and 90. In operation, the contact device shown in FIGURE 3 operates as follows:

Assume that the sprocket 82 is driven by the rotation of a timer, counter, or some other similar device. With the sprocket in the position illustrated, the armatures 80 and 92 are released and contacts 68 and 70 are open. As the sprocket 82 turns counter clockwise as suggested by the arrow, the blade 86 engages the lower end of the actuator 76 causing it to pivot in a clockwise direction about the pin 78. The pivotal action of the actuator in this direction moved the blade 72 carrying the contact 68 to the right. The light closure of the contacts closes the circuit 110 and energizes the coils. The coil 88 is such that only a very small current flow is required to attract its armature 92. Thus, the initial flow of current causes the armature 92 to move in a counter clockwise direction about its pivot 94. The counter clockwise movement of the armature 92 causes the flange 106 to engage the flange 102 of the actuator 76 and the actuator applies a greater pressure against the blade 72 to make a better closure of the contacts. Thus, chattering and hesitating of the contacts is eliminated and current flow increases. The increased current flow causes the energized coil 90 to attract the armature 80, and particularly its flange 112 to the pole piece 114. The pivotal action of the armature 80 about its support 104 raises the fulcrum 78 of the actuator 76 so that the lower end of the actuator lies above the upper end of the blade 86 of the sprocket 82. Moved upwardly in this manner, the actuator 76 steps-over the sprocket 82 and its upper end is released from the control of the arm of the armature 92. The flexible nature of the blade 72 urges the contact 68 to the left, out of engagement with the contact point 70. Little if any resistance to the action is encountered by the blade for the actuator 76 freely pivots on its support 78, the blade 86 of the sprocket 82 having passed beneath its lower end.

From the foregoing description, it will be apparent that each time a blade of the sprocket 82 engages the lower arm of the actuator, a tight closure and, thereafter, an opening of the contacts occurs. There can be no arcing between the contact points because of the substantially instantaneous release of the actuator 76. Chattering and hesitating of the switch action is eliminated because of the manner in which the armature 92 firmly closes the contacts during the first stage in the operation. Furthermore, false repetition of the action is totally eliminated.

In the embodiment of my invention shown in FIGURE 4, a similar arrangement is employed to cause the positive closing and opening of the contacts. In this embodiment, the contacts 120 and 122 are carried by flexible blades 124 and 126, respectively. The blade 125 extends downwardly below the contact 122 and lies in the path of the blades of the sprocket 128. The sprocket 128 is carried by a pivotally supported armature 130 biased to the position illustrated by the spring 132. The described structure is identical to that shown in FIGURE 2.

A second armature 134 pivotally supported on pin 136 has a flange 133 formed at one end which engages the blade 124 of the switch. The armature 130 pivotally supported on the pin 140 is controlled by a coil 142 energized through a circuit dominated by the contacts 120 and 122. The armature 134 is controlled by a second coil 144 which is also energized through the circuit controlled by the contacts 120 and 122.

Assume that the sprocket 128 continuously rotates in a counter clockwise direction as suggested by the arrow. As each blade of the sprocket engages the lower end of the blade 126, the contact 122 moves into engagement

with the contact 120 and current flows to the coils 142 and 144. Coil 144 is so wound so as to be more responsive to the initial flow of current and causes the armature 134 to pivot about its mounting 136 in a counter clockwise direction. Moved in that direction, the flange 138 of the armature 134 pushes the blade 124 carrying the contact 120 to the right so that the contacts are held firmly together. The firmer closing of the contacts causes more current to flow and coil 142 attracts the armature 130 against the bias of the spring 132. As the armature 130 moves downwardly to the pole piece of the coil 142, the blade 126 steps over the blade of the sprocket 128 and is released. The release of the blade 126 causes the contact 122 to move out of engagement with the contact 120 and the circuit is opened. The opening of the electrical circuits controlling the coils 142 and 144 causes each to release its armature so that the device returns to the position illustrated. Again, it will be appreciated that no false repetition of the closing of contacts 120 and 122 may occur, and arcing and chattering are eliminated. As explained in connection with the embodiment of FIGURE 2, the sprocket 128 normally would be driven either directly or indirectly by a gear (not shown) mounted coaxially with the pivot of the armature 130. As a result, the drive of the sprocket will not be disturbed by the movement of that armature. Furthermore, the arcuate movement of the sprocket 128 on the armature 130 will aid the blade 126 as it steps over the sprocket blades.

In FIGURES 5 and 6 another embodiment of my invention is illustrated. In this embodiment, a vertical plate 150 carries a pair of spaced apart contact fingers 152 and 154 on an insulation block 156. The plate 150 is supported by two pairs of parallel arms 158, 160 and 162, 164. Each of the arms is pivotally secured at one end to an edge of the plate 150 and at its other end to the support 166. The pins 168 which pivotally connect the ends of the arms 162 and 164 to the support 166 slide freely in slots 170 formed in the support. Thus, the pins 168 not only serve to support these arms for pivotal movement, but in addition, permit translational movement of the arms on the support 166.

Fingers 152 and 154 carry at their lower ends contacts 172 and 174 which are adapted to be closed by the metal strips 176 carried on the outer end of each of the blades 178 of the sprocket 180.

Disposed behind the plate 150 is a coil 182 secured by a frame 184 to the support 166. The coil 182 is controlled by a circuit dominated by the contacts 172 and 174.

The embodiment of the contact device shown in FIGURES 5 and 6 operates as follows:

Assume that the sprocket 180 is rotating counter clockwise as shown. As the metallic strip 176 engages the contacts 172 and 174, the coil 182 is energized and the plate 150 is attracted to it. The weight of the movable part of the parallelogram assembly which includes the plate 150 as well as the contact fingers supported from it along with the arms 158, 160, 162 and 164 preclude it from moving upward under the initial flux resulting from the light closure of the contacts. Rather, the arms 162 and 164 will move to the right in their slots 170 and the lower portion of the plate 150 will move toward the pole piece of the coil, and the plate will be at an angle to the vertical. This action of the plate 150 causes a firmer engagement of the strip 176 with the contacts 172 and 174 and an increased current flows through the coil 182. The increased current through the coil 182 will then cause the parallelogram assembly to move upwardly if a gap exists between the pole piece and the plate 150. The upward movement of the plate 150 carries the contact fingers 152 and 154 with it and they step over the end of the blade 178 of the sprocket 180. Thus, the circuit through the contacts 172 and 174 is broken and the coil 182 is deenergized. As a result, the parallelo-

gram assembly returns to the position shown with the contacts in the path of the next blade of the sprocket.

Those familiar with the art will appreciate that the embodiment of my invention shown in FIGURES 5 and 6 has the same advantage as the other embodiments of my invention. No arcing may occur between the contacts and once actuated the contacts close firmly and then open without any further control being exerted upon them. Further action on the part of the actuator is required to close the contacts again.

In each of the embodiments of my invention described above, the characteristic motion of the actuator is continuous and unidirectional. It should be understood that the invention, however, finds application in many other forms. Thus, the "step-over" principle may be applied to reciprocating motion which is either of a steady and predictable character or alternatively haphazard and unpredictable. In FIGURES 7-9, I have illustrated such an arrangement. Here, the actuator is controlled by and moves with an indicating pointer of an indicating instrument such as a volt meter, ammeter, temperature gage, pressure gage, position indicating servo, etc.

Referring to FIGURE 7, the reader will note that a pair of contacts 190 and 192 are carried on blades 194 and 196, respectively. The contacts lie in the path of travel of an actuator 198 carried on the pointer 200 of an indicating instrument generally designated at 202. As suggested by the broken line 204, the entire contact assembly is mounted concentric with the pointer shaft. The frame 206 of the assembly is supported at 208 on the shaft and thus, as the pointer 200 swings left or right from the neutral position shown, the actuator 198 engages one of the two contacts 190 and 192.

The blades 194 and 196 are carried on a parallelogram support which includes an armature 210 and a strut 214 pivotally mounted on the frame 206 by pins 212 and 216, respectively. Arms 218 and 220 are pivotally connected to the ends of the armature 210 and strut 214 and carry the blades 194 and 196 on insulation blocks 222 and 224 as illustrated.

The parallelogram support is controlled by a pair of coils 226 and 228 carried by the frame 206. The coils which as described below are alternately energized by the contacts 190 and 192 attract the armature 210 and rock the parallelogram assembly between the positions suggested diagrammatically in FIGURES 8 and 9. Thus, when the coil 228 becomes energized, the armature 210 pivots on the pin 212 and moves the assembly to the position shown in FIGURE 8. Energization of the coil 226 acts in a direction opposite to that of the coil 228 in that it pivots the armature 210 in a counter clockwise direction causing the assembly to assume the position shown in FIGURE 9.

The reader will note in FIGURES 8 and 9 that when the assembly pivots in response to energization of one of the coils, the contacts 190 and 192 move in a generally radial direction with respect to the axis 208 in opposite directions. Thus, when the coil 228 is energized, the contact 190 rises while contact 192 drops closer to the axis 208. Energization of the coil 226 produces the opposite effect.

The assembly shown in FIGURE 7 is suitable for use as a limiting device in combination with the indicator. The operation of the combination will be described as used for such a purpose. It will be noted in FIGURE 7 that I have suggested means at 260 and 262 which enable an operator to vary the distance between the contacts 190 and 192. Each arm 218 and 220 is a split and is secured together by pins 264 which may be assembled selectively in the various holes 266 provided. By varying the effective length of the arms, the distance between each contact and the center position of the pointer may be changed to alter the high and low limits.

As the assembly will not normally assume the position shown in FIGURE 7, but rather will be oriented

either as shown in FIGURES 8 or 9, assume that the assembly is rather in the position shown in FIGURE 8 with the contact 190 in the raised position. The spring 250 which extends between the pin 252 on the flange 254 which forms part of the strut 214 and the pin 236 on the frame 206 acts as a toggle and snaps the assembly into the positions shown in FIGURES 8 and 9. The particular position is determined by the position of the axis of the spring with respect to the center line defined by the pins 212 and 216. As the spring passes over center from one side of the line to the other, it snaps the assembly to the side approached. When the pointer 200 pivots counter clockwise on its shaft and the assembly is held by the spring 250 in the position of FIGURE 8, the contact 190 will be engaged by the actuator 198 and the coil 226 will be energized through the circuit which includes the leads 230 and 232, the lead 234, contact 190, actuator 198 and pointer 200, and the lead 236. Energization of the coil 226 will immediately cause the parallelogram assembly to snap to the position shown in FIGURE 9. When this occurs, the contact 190 is moved away from the actuator 198 and the circuit to the coil 226 is broken. This action, it will be recognized, is the same step-over action employed in the other embodiments of my invention. That is, as coil 226 is energized, the contact 190 is moved to the lower position out of engagement with the actuator 198. In the lower position, the contact 190 cannot again be engaged by the actuator to complete the circuit to the coil 226 until the other coil 228 has intervened. That is, until the coil 228 becomes energized to return the parallelogram assembly to the position shown in FIGURE 8, the actuator 198 cannot again engage the contact 190.

Now assume that the pointer 200 moves in a clockwise direction in response to an increase in the condition sensed by the indicator. When the pointer 200 moves far enough so that the actuator 198 engages the contact 192, the coil 228 becomes energized through the circuit which includes the leads 230 and 238, the lead 240, the contact 292, the actuator 198 and the pointer 200, and the lead 236. Energization of the coil 228 as stated above, causes the parallelogram assembly to snap to the position shown in FIGURE 8, and the contact 192 moves downwardly out of engagement with the actuator 198. Thus, in effect, the closing of the contact 192 immediately causes the circuit which is controlled by that contact to become de-energized. Here again, a signal could not be impressed upon the coil 228 until the other coil 226 is energized to intervene, for only then will the contact 192 again assume a position wherein it can be engaged by the actuator. Thus, the instrument shown in FIGURE 7 includes two step-over arrangements and one and only one signal can be produced each time the pointer 200 moves to an extreme position. Because of the manner in which the parallelogram assembly moves, no chattering or arcing can occur between the actuator 198 and either of the contacts.

In each embodiment of my invention, an output signal may be obtained as a result of each operation of the contact device by an electrical indicator or relay connected in series with the power source, i.e. in series with the coil causing the "step-over" action. In certain embodiments for certain applications it might be feasible to position an auxiliary pair of contacts to be operated by the coil and armature used for the "step-over" move-

ment. The auxiliary contacts could be connected into another electrical circuit and initiate the output signal. This, in effect, would combine the "step-over" coil with a relay and would result in a compact design desirable for certain applications.

Obviously, numerous modifications may be made of my invention without departing from its spirit. Therefore, I do not intend to limit the breadth of my invention to the specific embodiment illustrated and described. Rather, it is my intention that the breadth of my invention be determined by the following claims and their equivalents.

I claim:

1. A contact device comprising a pair of normally open contacts, a blade carrying one of the contacts, a coil, an energy source, a circuit including the contacts connected to the source and the coil and energizing the coil when the contacts close, a movable armature controlled by the coil, and an actuator carried by and movable with the armature and positioned to engage the blade and close the contacts only when the coil is deenergized, whereby the closing of the contacts moves the armature and causes the actuator to release the blade.

2. A device as defined in claim 1 further characterized by the movement of the armature causing the blade to step over the actuator.

3. A contact device comprising a pair of open contacts, a coil energized by the closing of the contacts, a pivotally supported armature pivoted to a first position by energization of the coil, means biasing the armature to a second position away from the coil when the coil is deenergized, and a sprocket carried by the armature and positioned to close the contacts upon its rotation when the armature is in the second position away from the coil, said sprocket passing beneath the contacts when the armature moves to its first position in response to energization of the coil.

4. A contact device comprising a pair of contacts movable to opened and closed positions, actuating means normally disposed adjacent the ends of and to one side of the contacts for moving the contacts to one of said positions, a coil operatively connected to the contacts and energized by the moving of the contacts to said one position, and an armature movable in response to energization of the coil and carrying one of the actuating means and contacts and positioning the actuating means relative to the contacts beyond the end of and to the other side of the contacts upon energization of the coil so that the contacts step over the actuating means and move to the other position, said armature being biased to a position wherein the actuating means is disposed in its normal position.
